DESIGN FOR A COMBINATION GLOVE AND HANDBAG

Marjorie Dunton, New York, N. Y.

Application January 26, 1939, Serial No. 82,610

Term of patent 7 years

To all whom it may concern:

Be it known that I, Marjorie Dunton, a subject of the King of Great Britain, residing at 761 Fifth Avenue, in the city, county, and State of New York, have invented a new, original, and ornamental Design for a Combination Glove and Handbag, of which the following is a specification, reference being had to the accompanying drawing, forming part thereof.

In the drawing:

Fig. 1 is a perspective view of a combination

glove and handbag embodying my design and showing the front of the glove member of the combination.

Fig. 2 is an end elevation of the same. The back of the glove shown in Fig. 1 is conventional, and the opposite side of the handbag member is the same as the side disclosed in Fig. 1.

I claim:

The ornamental design for a combination glove and handbag, as shown and described.

MARJORIE DUNTON.
